UNITED STATES PATENT OFFICE.

CLARENCE EDWARD STORCK, OF BALTIMORE, MARYLAND.

DISH-WASHING MACHINE.

,230,618.

Specification of Letters Patent. Patented June 19, 1917.

Application filed November 2, 1916. Serial No. 128,196.

To all whom it may concern:

Be it known that I, CLARENCE E. STORCK, a citizen of the United States, residing at city of Baltimore, in the State of Maryland, have invented certain new and useful Improvements in Dish-Washing Machines; and I do hereby declare the following to be a full, clear, and exact description of the invention, such as will enable others skilled in the art to which it appertains to make and use the same.

This invention relates to dish-washing machines, and has for an object to provide a machine of the class embodying the greatest degree of simplicity with convenience and efficiency.

A further object of the invention is to provide one or more buckets or tubs with a manually rotatable cage disposed therein and comprising new and improved features of efficiency and economy.

A further object of the invention is to provide a dish-washing machine of such nature that it can be made up of convenient size for ordinary household use, wherein the dishes may be washed, rinsed and dried expeditiously and without being touched by the hand.

With these and other objects in view, the invention comprises certain novel features of construction, combination and arrangement of parts as will be hereinafter more fully described and claimed.

In the drawings:

Fig. 1 is a view of the device, the tub being shown in diametrical section and the cage partly in elevation and partly in section.

Fig. 2 is a top plan view of the device, part of the lid of the cage being broken away to show the internal construction.

Fig. 3 is a perspective view of a slightly modified type of cage.

Fig. 4 is a detailed perspective view partly in section of the wired edge of the cage showing the wire forming a part of the securing means for the lid.

Fig. 5 is a detail view of the top wired edge of the cage, showing the use of the wire as a part of the hinge for the lid.

Like characters of reference designate corresponding parts throughout the several views.

The improved dish-washing machine which forms the subject-matter of the pres-

ent invention comprises one or more tubs 10, preferably formed tapering with the bottom smaller, for the reason that in an ordinary dish-washing outfit two or more of the tubs are furnished and it is desirable to nest the tubs and cage for convenience in shipping and storage. The tub is preferably composed of sheet metal having a wired upper edge shown at 11, and a chime 12 at the bottom supporting the bottom sheet 13 spaced some distance above the floor or table on which the device is resting. The tub is also preferably provided with a bail 14 which serves as convenient means for manipulating the tub either when filled or empty.

Within the tub 10 a cage is employed preferably composed of a sheet metal side wall 15 and bottom 16, and when so composed of sheet metal is provided with openings or perforations 17, both in the side wall and the bottom. The cage may, if found desirable, also be composed of wire as shown at Fig. 3. In either case, the cage is provided with a central pivot 18 which rests in a depression or indentation 19 in the bottom 13 of the tub. The cage is also provided with legs 20 shorter than the central pivot 18 so that the entire cage may rotate upon its pivot without the legs 20 engaging the bottom 13 of the tub, the clearance, however, being so little that when the cage is set on the table or the like the inclination of the cage is but slight. The legs also serve to hold the cage from slipping when it is elevated out of the tub and rests on the edge of the tub for draining the dishes contained in the cage.

The cage is provided with a cover or closure 21 in diameter slightly less than the internal diameter of the top of the tub so that while such closure 21 practically fills and closes the top of the tub, it nevertheless permits the rotation of and guides the cage within the tub, such rotation being facilitated by the two handles 22. The cover or closure 21 may be hinged to the cage in any approved manner, but it is preferably hinged by employing the upper wire of the reinforced edge to form a loop 23 as shown more particularly at Fig. 5, the cover having a sleeve 24 surrounding such wire loop 23. So that the handles 22 may serve for lifting the cage and its contained dishes into and out of the tub it is necessary that the

cover member 21 be attached to the cage by means in addition to the hinge. For such purpose a staple 25 is provided produced in any approved manner, but preferably by curving the reinforcing wire upwardly into such staple as indicated more particularly at Fig. 4. The cover member is provided with a slot 26 positioned to engage over the staple 25, and any fastening means as the hook 27 may be inserted through the staple 25 to secure the cover in position. So that the hook 27 may not become lost it is preferably secured to the cover in any approved manner as by the chain 28.

In operation, one of the tubs 10 is partially filled with a detergent solution sufficient to cover the dishes to be operated upon, while another similar tub is filled with clear water. Both of these baths are retained at or nearly at the boiling point to assist not only in removing the dirt accumulated upon the dishes, but also to more thoroughly sterilize the dishes, and when the dishes have been removed the heat of such dishes immediately dries the same without the use of absorbent or other drying means.

The dishes placed in the cage and the cover closed and secured, the cage is lifted into the tub containing the detergent bath by employing the handles 22. Once inserted in such tub and the spindle 18 properly seated in the socket 19, the whole cage becomes supported upon such central pivot and may be easily and conveniently rotated by manual operation, stress being applied to the handles 22. The cage and its contained dishes may be rotated and reversed until the detergent bath has thoroughly cleansed and sterilized the contained dishes. After the cleansing in the detergent bath the cage containing the dishes is lifted out of that bath and into the rinsing bath where a similar process is pursued in that the cage and contained dishes are rotated as found desirable in the rinsing bath. The rinsing being completed, the cage and contained dishes are lifted out, set upon the table or other convenient receiving means, and the heat of the dishes themselves almost instantaneously dries the water from their surfaces.

After the cage 15 is lifted from the tub it may be rested on the rim of the tub which permits the water to be drained from the dishes within the cage, and to prevent the latter from slipping off the edge of the bucket the bottom flange of the cage 15 may be roughened as by means of notches 15'

which will engage the edge of the tub to prevent the slipping of one or the other.

What is claimed as new is:—

1. A dish-washing machine comprising a tub, a cage centrally pivoted and rotatable within the tub and having a cover member 65 slidably fitting inside the top of the tub and forming a lateral support for the cage, means securing the cover upon the cage, and means to lift and rotate the cage.

2. A dish-washing machine comprising a 70 tub, a cage located within the tub and having a central pivot engaging a central bearing in the tub, a cover member secured to the cage and located within the top of the tub and being of a diameter slightly less 75 than the diameter of the top of the tub so as to have guided rotative relation therewith to support the cage upright, and means carried by the cover for rotating and lifting the cage.

3. In a dish-washing machine, a tub having an open top, a cage of lesser diameter than the tub and pivoted to rotate within the tub upon their major axes, a cover 80 hingedly secured to the cage and located within 85 and rotatively fitting the upper open end of the tub to support the cage upright, and spaced handles carried by the cover whereby the cage and cover may be handled or rotated in the tub.

4. A dish-washing machine comprising a tub having an open upper end, a cage centrally pivoted within the tub, an annular flange carried by the cage extending below such cage bottom but held out of engagement with the tub by the central pivot, said flange being provided with a notched annular bottom edge for the purpose of positively temporarily supporting the cage 95 against slipping when resting upon the rim 100 of the tub.

5. A dish washing apparatus comprising a tub having in the center of its bottom a bearing seat, a cage having a bottom portion provided centrally with a pivot to rest 105 in said seat of the tub, a cover movably connected to the cage and having diametrically opposite handles whereby the attached cage may be carried, or oscillated on its central bearing when disposed in the tub, the top 110 of the cage being below the rim of the tub, when inserted, and the cover being of such diameter as to rotatively fit within the tub at its rim and thus laterally support and guide the cage.

In testimony whereof I affix my signature.

CLARENCE EDWARD STORCK.
